UNITED STATES PATENT OFFICE.

CARL SCHWARTZ, OF ORWELL, NEW YORK, ASSIGNOR OF ONE-HALF TO MERVIN J. WEED, OF ORWELL, NEW YORK.

GRINDER.

1,159,108.

Specification of Letters Patent.

Patented Nov. 2, 1915.

Application filed November 10, 1914. Serial No. 871,337.

To all whom it may concern:

Be it known that I, CARL SCHWARTZ, a subject of the Emperor of Austria-Hungary, residing at Orwell, in the county of Oswego 5 and State of New York, have invented certain new and useful Improvements in Grinders, of which the following is a specification.

My invention relates to improvements in grinding devices, more particularly to devices of this character adapted to be employed in connection with the operating means of horse clippers and similar devices for sharpening the same, and has for one of its objects to improve the construction 15 and increase the efficiency and durability of devices of this character.

Another object of the invention is to provide a simply constructed device adapted to be coupled to the flexible shaft socket usually employed in connection with horse clipper and similar devices and to temporarily replace the same.

Another object of the invention is to provide a simply constructed attachment for a device of this character which receives the impact and wear of the abrasive member which may be renewed when worn at a trifling expense, and thus prevent the abrasive member from deteriorating the supporting parts.

With these and other objects in view the invention consists in certain novel features of construction as hereinafter shown and described and then specifically pointed out in 35 the claims; and in the drawings illustrative of the preferred embodiment of the invention—Figure 1 is a longitudinal sectional elevation of the improved device applied to a conventional flexible shaft coupling or 40 socket. Fig. 2 is a plan view of the improved device. Fig. 3 is a view similar to Fig. 1 illustrating a modification in the construction. Fig. 4 is a front view of the parts shown in Fig. 3 without the abrading member and its holding nut. Fig. 5 represents a plurality of the auxiliary protecting members of varying thicknesses.

Corresponding and like parts are referred to in the following description and indicated 50 in all the views of the drawings by the same reference characters.

The improved device is designed to be coupled to the ordinary tapered coupling socket of a flexible shaft, more particularly to a 55 flexible shaft employed in connection with

horse clipper devices and the like, but it is not desired to limit the invention to any specific construction of the driving mechanism, but for the purpose of illustration the improved device is shown associated with the conventional tapered socket usually employed in connection with flexible shafts and which includes a sleeve 10 having the usual flexible envelop or cover of the shaft coupled thereto, a portion of the flexible envelop being illustrated at 11 and coupled in the usual manner to the sleeve 10. The flexible shaft member, a portion of which is represented at 12, extends through the envelop 11 and into the sleeve 10, as shown in Fig. 1. 70

The improved attachment comprises a sleeve 13 having a tapered terminal 14 to engage in the tapered socket 10, as shown in Fig. 1. Mounted for rotation within the sleeve 13 is a shaft 15 having an eye 16 at 75 one end to enable it to be coupled to the flexible shaft 12. Rigidly secured to the shaft 15, preferably by shrinking therein, is a stop collar or disk 17 which bears by one face against one end of the sleeve 13 as 80 shown. The outer end of the shaft 15 is threaded to receive a holding disk 18 which is formed with a wrench receiving projection 19. The abrasive member, which is usually an emery wheel, and represented at 85 20, is mounted upon the shaft 15 between the members 17—18 and clamped in position by actuating the members 18—19 with a wrench or like implement in the usual manner.

The shaft 15 is formed with an annular 90 channel 21 with which the inner end 22 of a threaded plug 23 engages, to hold the shaft from longitudinal movement relative to the sleeve.

By this simple means, when it is desired to employ the grinding element, the horse clipper device, or other implement which may be engaged in the socket 10, is detached and replaced by the socket 13—14, the latter being coupled to the flexible shaft by the eye 16 so that when motion is imparted to the flexible element 12 the grinder element 20 will be actuated or correspondingly rotated. By providing the stop member 17 and rigidly coupling the same to the shaft, 105 the wear or friction is borne entirely between the members 17—13 and the parts thus protected from abrasive action from the member 20.

In Figs. 3 and 4, a slight modification in 110

the construction is shown consisting in forming the shaft 15 with a reduced portion 24 whereby an annular shoulder 25 is produced. In the modified structure a recess 26 is formed in the face of the member 17, and a washer 27 disposed over the reduced portion 24 of the shaft and within the recess 26, the washer being sufficiently thick to project a short distance beyond the outer 10 face of the recessed member 17, as shown in Fig. 3, so that the abrading member 20 will bear against the washer and not against the member 17. Thus the washer 27 receives all the friction and the member 17 is 15 protected from abrasion from the member 20. The members 27 are inexpensive and may be renewed at small cost when worn, thus extending the "life" of the device. A plurality of the members 27 of varying 20 thicknesses will preferably be provided with each device, so that the members 20 of correspondingly varying thickness may be employed without discarding the remaining portion of the device by simply substituting 25 washers 27 of a thickness to correspond to the thicknesses of the members 20. Thus the same sleeve and other parts may be employed for abrading members of various sizes.

20 The washers 27 may be of any suitable

material but will preferably be of tempered steel, and operate as a protector to the portion 17 of the sleeve.

The improved device is simple in construction, can be manufactured and applied without material increase of expense, and enables the same power, including flexible shaft and its socket, to be employed for a variety of purposes.

Having thus described the invention, what 40 is claimed as new is:—

In a device of the class described, a sleeve externally tapered toward one end and with a lateral flange at the other end, said flanged end having a seat extending into the flange, 45 a shaft extending through said sleeve and with means at one end adapted to receive a shaft coupling, a shaft cover having an internally tapered socket for engaging the externally tapered portion of the sleeve, an 50 annular bearing member engaging said seat, and means adapted to clamp an abrading element upon said shaft and against said bearing member.

In testimony whereof I affix my signature 55 in presence of two witnesses.

CARL SCHWARTZ. [L.S.]
